UNITED STATES PATENT OFFICE.

EDMUND NOLAN, OF DETROIT, MICHIGAN.

HOOD CLAMP.

Application filed July 24, 1922. Serial No. 577,211.

To all whom it may concern:

Be it known that I, EDMUND NOLAN, a citizen of the United States of America, residing at Detroit, in the county of Wayne and State of Michigan, have invented certain new and useful Improvements in Hood Clamps, of which the following is a specification, reference being had therein to the accompanying drawings.

10 The invention relates to the manufacture of hood clamps designed for use upon automobiles to clamp the base of the hood to the frame. Usually such clamps are formed of a hollow handle member having a projecting lug or catch and a spring-pressed plunger within the hollow handle having a downwardly extending shank which is pivotally attached to the frame. Thus the tension of the spring is exerted to draw the 15 lug or catch downward upon the hood, but will yield for the disengagement of the catch when desired. It is the object of the present invention to simplify the process and reduce the cost of manufacture by forming the 20 handled portion of the clamp of pressed sheet metal.

In the drawings:

Figure 1 is a plan view of the sheet metal blank from which the hood clamp handle 30 is formed;

Figure 2 is a longitudinal section illustrating one step in the operation of forming the handle;

Figure 3 is a similar view after a succeeding operation;

Figure 4 is a plan view of Figure 3;

Figures 5, 6 and 7 are respectively a plan view, front elevation and side elevation of the lug or catch;

40 Figures 8 and 9 are respectively a plan view and a sectional side elevation of the cap member;

Figure 10 is a longitudinal section through the completed handle showing the plunger and spring in engagement therewith.

Figure 11 is a view similar to Figure 10 showing the modified construction.

My improved clamp is formed from an 50 oblong sheet metal blank A, which is pressed to cup the central portion thereof, as indicated at B in Figure 2, and to simultaneously bend upward the opposite end portions and to fashion the same into substantially semi-circular cross-section. These end portions are then further fashioned, as

shown in Figure 3, the portion thereof constituting complementary sections of a cylindrical housing C and the end portions being bent to form oppositely extending handle flanges D. The portion C is further provided intermediate its ends with an annular shoulder E for receiving a ring or ferrule F having the lug or catch projecting therefrom. This ring or ferrule may 60 also be formed from pressed sheet-metal which is struck up to form the ring proper and a projecting flange, the latter being return-bent to extend upwardly, as indicated at F', and then bent downward at G to 70 form the catch. H is a cap for closing the upper end of the cylindrical housing, which, as shown in Figures 8 and 9, may also be pressed from sheet metal. This cap is preferably retained in engagement with the 75 portion C by forming it with an annular groove I therein and forming at the upper end of the member C an inwardly extending bead J for engaging said groove. K is a ring or ferrule surrounding the portion 80 C at the upper end thereof, which holds the two complementary sections from spreading and also retains the cap in engagement.

With the construction as described, during the process of manufacture, before the cap 85 is engaged a plunger L having a shank M is inserted within the cylindrical portion C, the shank passing downward through an aperture N in the cupped portion of the blank. A spring O is also sleeved upon the 90 shank M, one end abutting against the plunger L and the other end against the bottom of the cup-shaped portion. Thus the tension of the spring will hold the plunger normally pressed against the cap 95 H, but when an upward pull is exerted upon the handle, the spring will be compressed and the handle raised sufficiently to disengage the catch G from the hood.

In the modified construction shown in 100 Figure 11, instead of forming the portions D integral with the portion C, such portions may be separately formed but integral with a ring or ferrule P. This ring is then sleeved upon the portion C and engages a 105 shoulder Q at the upper end of said portion, which prevents detachment therefrom. The portion also has an outwardly extending projection R extending longitudinally of its upper end which engages in a correspondingly shaped recess in the ring P to prevent 110 rotation of the ring about the housing.

The construction described may be cheaply manufactured, requiring no machining operations, with the exception of the plunger, shank and spring being formed entirely from pressed sheet metal.

What I claim as my invention is:

- 5 1. A hood clamp comprising a hollow casing having complementary segmental portions integrally connected at one end, laterally extending handle portions at the opposite end, a cap for closing said opposite end, and a ring or ferrule sleeved upon said casing having a catch projecting laterally therefrom.
- 10 15. 2. A hood clamp comprising a hollow cylindrical casing formed of complementary segmental portions integrally connected by a cup-shaped portion at one end of the casing, handles at the opposite end of said casing projecting laterally therefrom, and a cap for closing said opposite end of the casing inserted within the segmental portions thereof and having a groove and bead engagement therewith.
- 20 25. 3. A hood clamp comprising a hollow casing formed of complementary segmental portions integrally connected by a cup-shaped portion at one end thereof, said cup portion being centrally apertured for the passage therethrough of a shank, handles
- 30
- 35 40 45 50 55 projecting laterally from the upper end of said casing, a cap for closing said upper end provided with a grooved flange for engaging a beaded portion of the casing, a ferrule for surrounding the casing to retain said bead and groove in engagement, and a ferrule sleeved on said casing having a catch projecting laterally therefrom.
4. A hood clamp comprising a hollow casing formed of complementary segmental portions integrally connected by a cup-shaped portion at one end thereof and provided with laterally projecting handles at the opposite end thereof, said hollow casing being further provided intermediate its ends with an annular shoulder, and a ferrule sleeved upon said casing and abutting against said shoulder and having a catch projecting laterally therefrom.
5. A hood clamp comprising a hollow casing formed of complementary segments integrally connected at one end, a handle projecting laterally from each of the segments of said hollow casing, and a ring or ferrule sleeved upon said casing and retaining the segments thereof together, said ring having a catch projecting laterally therefrom.

In testimony whereof I affix my signature.

EDMUND NOLAN.
